UNITED STATES PATENT OFFICE.

ROBERT JOSIAH STANFIELD, OF KAUFMAN, TEXAS.

DRAWHEAD.

Application filed March 16, 1922. Serial No. 544,284.

To all whom it may concern:

Be it known that ROBERT JOSIAH STANFIELD, a citizen of the United States of America, residing at Kaufman, in the 5 county of Kaufman and State of Texas, has invented new and useful Improvements in Drawheads, of which the following is a specification:

The object of the invention is to provide 10 a draw head for car couplers of the Janney type wherein a simplified mounting and means for locking and releasing the knuckle is provided to facilitate the coupling and uncoupling of cars particularly without involving 15 the trainmen or operatives in the risk incident to entering the space between cars; and with this object in view the invention consists in a construction and combination of parts of which a preferred embodiment is shown in the accompanying drawings, wherein:—

Figure 1 is a side view, and

Figure 2 is a plan view of a pair of 25 couplers embodying the invention arranged in interlocking or engaged relation.

Figure 3 is a horizontal sectional view of one of the draw heads showing in full lines the locked and in dotted lines the unlocked or open position of the knuckle.

Figure 4 is a front view, and

Figure 5 is a vertical longitudinal sectional view of two coupled heads.

Figure 6 is a perspective view of one of the knuckles.

Figure 7 is an inverted plan view of a 35 portion of one of the heads to show the knuckle actuating spring.

The draw head 10 as in the well known form of the Janney type of coupler is provided 40 with the fixed jaw 11 at one side and the movable jaw or knuckle 12 at the opposite side mounted for swinging movement on a vertical axis by means of a bolt 13 and adapted for swinging movement inwardly or toward the fixed jaw for engagement with the corresponding movable jaw or knuckle of the complementary draw head carried by the adjacent end of the car to be coupled.

50 The movable jaw or knuckle carries an inwardly extending arm 14 disposed between the planes of the upper and lower surfaces of the draw head and adapted for swinging movement in a throat 15 represented by a 55 cut away portion of the body of the draw head, and arranged in intersecting relation

with the throat is a guide opening 16 for a vertical movable locking pin 17 projecting below the lower side of the draw head for connection with the horizontal arm of a bell 60 crank lever 18 fulcrumed upon the draw head:

The knuckle carried arm is provided at its under side with a bevel face 21 and the upper end of the locking pin is correspondingly bevelled as shown at 22, so that with the parts in the open or receiving position pressure applied to the arm by the entrance into the head of the knuckle or movable jaw of an opposing head will in repressing the 70 said arm depress the locking pin sufficiently to permit of the arm passing thereover and thus permitting the knuckle to be moved to its engaging or operative position where it is locked by the return of the pin to its upper or normal position.

The knuckle is yieldingly impelled to an open position by a spring 23 which in the construction illustrated is coiled upon the pivot bolt of the knuckle, and the substantially horizontal arm of the bell crank lever is slotted as indicated at 24 to receive the reduced lower end of the locking pin which in turn carries a removable key 24 for preventing accidental disengagement.

The bell-crank lever is yieldingly actuated to hold the locking pin in its upper or locking position by a spring 25 interposed between an intermediate portion of the upright arm of said lever and the side of the 90 draw head while connected with the upper end of the upright arm of said bell-crank lever through a suitable slotted connection is an operating lever 26 having a terminal ring 27 with which may be connected an 95 operating chain 28, extending for example to the side of the car for manipulation by the brakemen or trainmen without passing between the ends of the cars.

In the construction illustrated the adjacent ends of the operating bell-crank levers are slotted as indicated respectively at 29 and 30 for the reception of a bolt 31 of which the nut 32 may be tightened to lock the same at any desired adjustment in the slot 30.

100 From the above description it will be seen that the locking or the coupling of the device is accomplished automatically by the contact of the knuckle or movable jaw of one head with the knuckle carried arm of the 110 other head, and the repression of said arm to swing the knuckle which carries the same

inwardly into engaging relation with the knuckle of the approaching head; and that the unlocking or release of the coupler is accomplished by the movement of the operating lever sufficient to disengage the locking pin from the knuckle carried arm and permit the knuckle actuating spring to throw the knuckle to the release position shown in dotted lines in Figure 3.

10 Having described the invention, what is claimed as new and useful is:—

15 1. A coupler having a draw head of the Janney type wherein the knuckle or movable jaw is provided with an inwardly projecting arm rigid with the knuckle for operating in a throat of the head, a vertically movable locking pin extending upwardly from the lower side of the draw head and yieldingly impelled upward for intersection with the 20 path of movement of the said arm, and means for retracting the pin to release the knuckle and consisting of a spring actuated bell-crank lever having connection with the operating pin and an operating lever mounted upon the draw head and having a pin 25

and slot connection with the bell-crank lever.

2. A coupler having a draw head of the Janney type wherein the knuckle or movable jaw is provided with an inwardly projecting arm rigid with the knuckle for operating in a throat of the head, a vertically movable locking pin extending upwardly from the lower side of the draw head and yieldingly impelled upward for intersection with the path of movement of the said arm, and 30 means for retracting the pin to release the knuckle and consisting of a spring actuated bell-crank lever having connection with the operating pin and an operating lever mounted upon the draw head and having a pin 35 and slot connection with the bell-crank lever, said pin and slot connection including longitudinal slots in the adjacent portions of said operating and bell crank levers and a bolt 40 engaging and adjustably mounted in one 45 of said slots and engaged by the other.

In testimony whereof he affixes his signature.

ROBERT JOSIAH STANFIELD.
